UNITED STATES PATENT OFFICE.

IRA E. WEEL, OF CLEVELAND, OHIO.

AUTOMATIC CUT-OFF DEVICE.

SPECIFICATION forming part of Letters Patent No. 783,341, dated February 21, 1905.

Application filed December 28, 1903. Serial No. 186,836.

To all whom it may concern:

Be it known that I, IRA E. WEEL, a citizen of the United States of America, and a resident of Cleveland, in the county of Cuyahoga and State of Ohio, have invented certain new and useful Improvements in Automatic Cut-Off Devices, of which the following is a specification.

My invention relates to improvements in cut-off devices, being particularly applicable to and herein described as an automatic valve-control mechanism for closing the outlet of a natural-gas pipe upon the reduction of pressure and gas-supply therein below a predetermined point.

The object of my invention is the production of a pressure-controlled device of extreme simplicity and cheap construction for positively operating a suitable valve part for this and analogous purposes.

It has been a commonly-observed occurrence that the pressure in natural-gas mains especially is liable to such fluctuations or stoppage that lighted burners connected therewith are extinguished, and upon the resumption of the normal gas-supply escaping gas is a source not only of marked discomfort and inconvenience, but of great danger and loss through the explosion of the gas. Accordingly I have endeavored to overcome this serious disadvantage by the provision of the simplest possible type of positively-acting device for permanently shutting off automatically the flow of gas under the circumstances indicated. This I have accomplished by means of a controlling part regulated by the flow of gas acting in opposition to a weight or its equivalent, which in turn governs suitable valve mechanism. My invention, however, very obviously can be made much more readily understood by referring to the accompanying drawings, illustrating an embodiment thereof.

Figures I and II are longitudinal sectional views of a mixer-chamber for gas to which my invention has been applied, the valve device and controlling parts being shown, respectively, in their open and closed positions. Fig. III is an end view thereof, partially broken away to illustrate the interior, the valve being closed.

The same character of reference is used to designate similar parts in each of the foregoing figures.

Although not necessarily associated with the gas-mixer, my improvements may very conveniently be applied thereto, and I have chosen to describe the same in connection therewith.

In the drawings the mixer-chamber *m* is shown provided with the usual air inlets or openings *o*, being forwardly tapped at *f* to receive the burner connection and rearwardly at *r*, wherein the supply-pipe may be fitted. It will be understood that the manually-operated valve governing the gas-supply to the mixer and burner would be located in said pipe, which is not shown in the drawings. An entrance from the supply-pipe to the mixer-chamber is provided in the opening or inlet *i*, wherein is seated the tapering or needle valve part *n*. At the outer extremity thereof is screwed an obstructive part or cup *c*, having a rear stop *s* to engage the casing, while the other end of the valve part *n* is loosely connected with the lever *l*, pivoted within the wall of the mixer-chamber. A weight *w* swings independently from its own pivot at the lower end of said lever, in an overbalanced position. The several parts are so designed that the flow of gas within the supply-pipe will more than counterbalance the weight when it is in the position shown in Fig. I, by reason of the obstructive action, slight though it be, of the cup *c*, guarding the inlet or opening. Thus when the manual valve is opened and the cut-off appliance adjusted in the manner shown gas will continue to flow to the burner so long as the gas pressure or flow is maintained above the predetermined point at which it is desired that the appliance shall act, the weight being opposed by the flow of gas.

This results by reason of the maintenance of the weight in a position of unstable equilibrium, but supported by the obstructive or impeding part provided in the cup *c*, whereon the flow of gas acts to maintain the connected valve part in open position and support the very slight weight normally exerted by the arrangement shown. The adjustable stop *s* prevents undue inward movement of the valve part, while to

meet varying conditions the cup *c* may be replaced by one of smaller or even slightly larger diameter suitable to different gas-pressure. Indeed, for a relatively low gas pressure or 5 flow an auxiliary tapering tube *a*, as indicated in Fig. I, may be introduced when needed to direct the full flow of gas centrally within the cup or equivalent obstructing part. Immediately the flow of gas is checked or ceases from 10 any cause, however, it will be seen that the weight at once acts to rock the lever on its pivot, closing the needle-valve and forcing it home in turn by the outward swing of the weight upon its pivot at the end of said lever, 15 just as indicated in Fig. II. Thus the valve will remain closed until its controlling parts are again adjusted, even though the full pressure of gas is once more maintained, the device being governed by the flow of gas when properly established through its controlled outlet. 20 Accordingly the appliance affords an immediate and automatic protection against the accidental escape of gas or other fluid placed under its control.

25 Having now explained one embodiment of my invention, I claim as new, and desire to secure by Letters Patent, the following:

1. In a device of the class described, the combination with a valve-inlet, of a valve part 30 controlling the same, its connected obstructive part disposed on the inlet side of the valve in the supply-pipe and adapted when held in its open position by the flow of gas to permit the continuance of such flow, and an opposing element adapted automatically to seat the valve part under predetermined conditions, 35 substantially as set forth.
2. In an automatic cut-off appliance, the combination with the valve-inlet permitting 40 the flow of gas to the burner, of a valve part designed to close the same, an impeding element connected to actuate the latter, disposed in the path of the controlled gas within the supply-pipe on the inlet side of the valve, and 45 a weight opposing the action of the flow of gas upon said element and adapted to seat the connected valve part upon the reduction in the flow of gas, substantially as set forth.
3. In an automatic cut-off appliance, the 50 combination with a valve-inlet, of a valve part

controlling the same, an obstructive or impeding part in the supply-pipe on the inlet side of the valve, adapted under normal conditions to permit the flow of gas past it and to maintain the valve part in its open position, a lever connected with said valve part, and a weight acting upon the lever in opposition to the impeding part and adapted to close the valve under predetermined conditions, substantially as set forth. 55 60

4. The combination with the mixer-chamber, of the valve-inlet connecting with the supply-pipe, the needle-valve therein, the cup or impeding part in the supply-pipe before the inlet, the lever connected with the needle-valve part, and the weight independently pivoted thereon in position to force said valve part to its seat upon the reduction in pressure in the supply-pipe, substantially as set forth. 65

5. In an automatic gas-cut-off appliance, the 70 combination with the controlling-valve, of an obstructive part positioned before the valve-inlet to permit the flow of gas past it under normal conditions of such flow; the same comprising a reciprocating plunger carrying an 75 impeding portion in the supply-duct, against which the flow of gas is directed initially, and means acting in opposition to the flow of gas, associated with the valve mechanism and adapted to close the same until released, upon 80 the cessation of the flow of gas, substantially as set forth.

6. In an automatic gas-cut-off appliance, the combination with the controlling-valve, of an 85 obstructive part in the supply-pipe on the inlet side of the valve, influenced by the continuous flow of gas to maintain the valve open, and an overbalanced weight associated with these parts and opposed by the current of gas, adapted under predetermined conditions automatically to seat the valve part and prevent the subsequent flow of gas, substantially as set forth. 90

Signed at Cleveland, this 26th day of December, 1903, in the presence of two subscribers. 95
